UNITED STATES PATENT OFFICE

2,574,640

CONTINUOUS FEED BRAKE SHOE
GRINDING FIXTUREFrank A. Harper and John M. Graham,
Paulding, Ohio

Application October 7, 1949, Serial No. 120,074

3 Claims. (Cl. 51—108)

1

This invention relates to improved apparatus for removing brake lining from automotive brake shoes, the primary object of the invention being to provide efficient and relatively low-cost, power-driven apparatus of this character employing magnetic feed wheels for mounting and feeding a brake shoe against a grinding wheel or other abrasive agent, the feed wheels being of different diameters to accommodate different sizes of brake shoes.

Another important object of the invention is to provide apparatus of the character indicated above wherein the feed wheels have locking means actuated by rotation of the wheels to secure the brake shoes in place thereon during removal of the brake lining; means for releasing the locking means upon rotation of the wheels to positions in which the lining-removal operation has been completed; and ejecting means acting to remove the brake shoes from the feed wheels upon completion of the lining-removal operation.

Another important object of the invention is the provision of apparatus of the above-indicated character which acts to clean and recondition the face of the brake shoe while removing the lining therefrom, and in which provision is made for operation of the feed wheel at slow, intermediate or high speeds.

A further important object of the invention is the provision of apparatus of the character indicated above which can be built with integral abrasive or cutting means or which can be provided as a power-driven feed wheel attachment adapted to be applied to existing abrasive or cutting means.

Other important objects and advantageous features of the invention will be apparent from the following description and the accompanying drawings wherein, for purposes of illustration only, specific embodiments of the invention are set forth in detail.

In the drawings:

Figure 1 is a rear end elevation of one embodiment;

Figure 2 is a fragmentary right-hand side elevation thereof; partly in section;

Figure 3 is an enlarged fragmentary detail of the feed wheel, showing the brake shoe in section and clamped or locked therein;

Figure 4 is a fragmentary right-hand side elevation, with the outer feed wheel disc removed;

Figure 5 is a transverse vertical section taken on the line 5—5 of Figure 2;

Figure 6 is a horizontal section taken on the line 6—6 of Figure 2;

2

Figure 7 is a fragmentary right-hand side elevation, showing the graduated hand wheel enabling vernier adjustment of the approach of the feed wheel to the grinding wheel;

Figure 8 is a fragmentary right-hand side elevation of another embodiment involving different brake shoe locking means showing application of a brake shoe on the feed wheel to the grinding wheel;

Figure 9 is an enlarged, fragmentary exploded view of said different brake shoe locking means;

Figure 10 is a fragmentary right-hand side elevation of Figure 9.

Referring in detail to the drawings, wherein

15 like numerals designate like parts throughout the several views, and in particular to Figures 1 to 8 thereof, the numeral 12 generally designates the base adapted to be secured on a suitable support (not shown) and comprising a plate 13 having 20 risers 14 and 15 at its forward and rearward ends, and an intermediate riser 16 spaced therebetween. A vernier screw shaft 17 is slidably journaled in the risers. Spaced at opposite sides of the shaft 17 are slideways 18 on which are 25 slidably mounted the front and rear blocks 19 and 20, respectively, depending from forward and rearward portions of the retracting carriage 21. In the extreme rearward position of the carriage 21 the rear block 20 engages the rearward base 30 riser 15, as shown in Figure 2. Helical springs 22 are circumscribed on the slideways 18 and compressed between the intermediate riser 16 and the rear slide block 20, whereby the carriage 21 is normally urged rearwardly in a direction toward the grinding wheel.

35 The rearward end of the vernier screw 17 is threaded through the front carriage slide block 19, as shown in Figure 6, and has its rear end journaled in the intermediate riser 16 at 23. A vernier hand wheel 24 is pinned on the forward end of the shaft 17, as indicated at 25, and a graduated dial 26 is positioned on this shaft between the hand wheel 24 and the forward riser 14. The hand wheel 24 is adapted to be turned 40 in the proper direction to move the carriage 21 away from the grinding wheel against the resistance of the springs 22 and thereby determine the amount of brake lining to be removed by the grinding wheel. The springs 22 serve to enable 45 the proper feeding of out-of-round brake shoes to the grinding wheel and also as cushioning means, preventing damage to the machine by permitting the carriage 21 to yield whenever an object otherwise too large to pass falls between 50 the brake shoe being ground and the grinding wheel.

55 Figure 7 is a fragmentary right-hand side elevation, showing the graduated hand wheel enabling vernier adjustment of the approach of the feed wheel to the grinding wheel;

The retracting carriage 21 comprises the plate 27 having transverse risers 28 and 29 at its forward and rearward ends, respectively. A base plate 30 forming part of the housing or frame 31 rests slidably on the plate 27 and is shorter than the distance between the risers 28 and 29, so that the frame 31 can be shifted along the plate 27 toward and away from the grinding wheel to accommodate feed wheels for brake shoes of different sizes. A spacer block 32 having a handle 33 is adapted to be positioned to take up the space at either end of the base plate 30 and the related one of the risers 28 and 29.

Longitudinal hold-down clamps 34 are bolted at their ends, as indicated at 35, to the risers 28 and 29 and have depending longitudinal ribs 36 engaging in grooves 37 formed in the housing base plate 30, whereby sidewise shifting of the housing or frame 31 relative to the carriage 21 is precluded.

The housing or frame 31 is generally rectangular in form and has an electric motor 38 mounted on the upper end thereof having a belt pulley 39 positioned beyond the left-hand side thereof in vertical alignment with a belt pulley 40 positioned therebelow on a shaft 41 of a reducing gear 42, which is operatively connected in a conventional manner (not shown) with the feed wheel shaft 43 which projects from the right-hand side of the housing 31.

The feed wheel 45 comprises an inner disc 46 having a spacing annulus 47 on its right-hand or outer side, providing a circular recess 48, as shown in Figure 5. The outer disc 49 has on its inner side a flat, cylindrical portion 50 adapted to fit in the recess 48. The inner disc 46 is circumposed directly on the shaft 43 and the outer disc 49 is traversed by a threaded spindle 51 which threads into a threaded bore 52 in the shaft 43, the spindle having a hand wheel 53 on its outer end adapted to be turned to bear against a washer 54 engaging the outer side of the outer disc to clamp the discs together non-rotatably on the feed wheel shaft 43.

The feed wheel discs are substantially solid and have their peripheral edges indented to provide seats for horseshoe permanent magnets 55 having their poles 56 flush with the peripheries of the discs, the magnets being equally spaced around the peripheries of the discs. Between adjacent magnets 55 are radial pivots 57 on which are retainably pivoted segmental, eccentric locking discs 58 with their curved edges substantially concentric with the pivots 57. While disengaged, the locking discs 58, which are aligned in opposed pairs, occupy the positions shown in Figure 1. During actual use, the abrasive wheel 70 travels faster than the wheel 45 and thereby produces a tendency for the brake shoe 60 to travel on the feed wheel 45 in a clockwise direction. Since the curved edges of the locking discs 58 engage the web 59 of the brake shoe 60, the movement of the brake shoe causes the paired locking discs 58 to swing toward each other to clamp therebetween the web 59 of a brake shoe 60 with the magnets 55 acting upon the arcuate flange 61 in which the lining 62 is secured to hold the brake shoe 60 on the periphery of the feed wheel 45.

A bracket 63 is mounted on the forward end 70 of the upper part of the frame or housing 31, as indicated at 64, and projects toward the feed wheel 45 and terminates in a stub shaft 65 on which is pivoted the upper or forward end of an ejecting pin or lever 66. The lever 66 has the 75

slightly-downwardly, longitudinally-curved form shown in Figure 4, and the upper edge 67 of its forward end is arranged to ride under the spacer annulus 47 of the inner feed wheel disc 46, while the lower edge thereof is tapered at 68 to ride upon portions of a brake shoe on the feed wheel in a manner hereinafter described.

A power-driven grinding wheel 70 is adapted to be suitably supported behind the feed wheel 45 with its axis in horizontal alignment with the axis of the feed wheel, and the grinding wheel is rotated counterclockwise and faster than the feed wheel, so as to impart a tendency to the brake shoe to travel on the feed wheel in the same clockwise direction as the feed wheel and wedge the locking discs 58. In placing a brake shoe 60 for grinding, the brake shoe is placed on the feed wheel so that the rearward end of the brake shoe flange 61 meets the grinding wheel 70 at or near the center line of the most rearward arc of its traverse. As the feed wheel with a brake shoe installed thereon, as described, continues its rotation, the brake shoe 60 passes the grinding wheel 70 and is completely stripped of its lining 62 as well as of any other foreign matter present on the face of the shoe. As the feed wheel 45 continues its rotation and the brake shoe 60 passes the center line of the lowest arc of its traverse, the eccentric locking discs 58 are released from clamping engagement with the web 59 of the brake shoe 60 by being engaged by the ejecting lever 66, the action of gravity upon the locking discs, the rotation of the feed wheel 45, and the absence of engagement of the brake shoe with the grinding wheel. The position of the brake shoe 60 just prior to ejection by the lever 66 is clearly shown in phantom in Figure 8 of the drawings. As the feed wheel 45 moves through this position, the cleaned brake shoe is forced against the under side of the ejecting lever 66 and is thereby forced downwardly off the feed wheel 45 against the pull of the magnets 55, to be disposed of as the operator sees fit.

The amount of material to be removed from a brake shoe is determined by adjusting the carriage 21 toward or away from the grinding wheel 70 by turning the hand wheel 24 so as to turn the micrometer screw 17 and move the retracting carriage 21 on the base 12, thereby determining the distance between the feed wheel 45 and the grinding wheel 70, the amount of the adjustment being shown by the dial 26.

The machine is adapted to recondition brake shoes of various diameters through the use of feed wheels 45 of different diameters, which are easily removed and installed on the shaft 43 by removing the spindle 51 by means of the hand wheel 53 and replacing the feed wheel present on the shaft 43 with another of the correct diameter. The spacing blocks 32 are used at either end of the carriage 21 in accordance with whether the feed wheel present is replaced by a smaller or a larger feed wheel. A number of the spacing blocks 32 are provided to enable the necessary adjustment of the housing 31 relative to the carriage 21.

Referring to Figures 2 and 3, there is therein shown means for more positively and reliably clamping the locking discs 58 against opposite sides of the web 59 of the brake shoe 60. This means takes the form of vertical arms 71 depending at opposite sides of the feed wheel 45 from a bracket 72 secured to the rear of the housing 31, these arms having arcuate shoes 73 on their

lower ends arranged concentrically with respect to the feed wheel 45. The shoes 73 have rounded approach ends 74, positioned to cam the locking discs 58 toward each other into clamping engagement with the related sides of the brake shoe web 59, as shown in Figure 3, as the feed wheel rotates clockwise into a position in which the brake shoe 60 is applied to the grinding wheel. When the locking discs concerned pass beyond the exit end of the shoes 73, the locking discs are free to be released in a manner already described hereinabove.

In Figures 8 to 10 is shown another form of brake shoe clamping means, as a substitute for both of the above-described forms of locking disc arrangements. As shown in Figure 9, the inner and outer discs 46 and 49 of the feed wheel 45 are formed with transverse bores 75 opening at their opposite ends in concentric larger-diameter recesses 76 and 77, respectively. A shank 78 slides in each bore 75 and has a circular locking disc 79 on its inward end and a dish-like head 80 on its outer end, with a helical expanding spring 81 circumscribed on the shank 78 and compressed between the related wheel disc and the head 80, whereby the locking disc 79 is normally retracted out of clamping engagement with the brake shoe web 59 and the head 80 extends outwardly from the related wheel disc and into the path of a related actuating shoe 73 having a rounded approach end 74, as in the embodiment of Figures 2 and 3, whereby the locks are pressed inwardly by the shoes 73 to engage opposite sides of the brake shoe web 59. As the heads 80 pass beyond the actuating shoes 73, the springs 81 retract the locking discs 79 from the brake shoe web 59 and into the recesses 76. In the impressed position of the locks, the heads 80 seat in the recesses 77.

What is claimed is:

1. In a machine for grinding off the lining of an arcuate brake shoe, a base, a carriage mounted on said base for endwise movement relative to said base, a grinding wheel mounted stationarily at one end of the base and the carriage, a transverse shaft journaled on said carriage, means operatively connected to said shaft for rotating said shaft, a feed wheel fixed on one end of said shaft in the plane of said grinding wheel, said feed wheel comprising a pair of axially spaced discs having peripheral edges on which a brake shoe is adapted to be circumferentially engaged with the web of the shoe extending radially inwardly from the shoe into the space between the discs, first securing means on said discs for removably securing the brake shoe on the peripheral edges of the discs, and second securing means on said discs engageable with opposite sides of the shoe web, adjusting means connected between said base and said carriage for adjusting said carriage endwise on the base for engaging the lining of the brake shoe with the grinding wheel, said second securing means comprising radial pivot pins on the peripheral edges of the discs, locking discs mounted on said pivot pins to swing toward and away from adjacent sides of the shoe web, and locking members on said carriage extending along opposite sides of said feed wheel and engageable with the locking discs to hold the locking discs in engagement with the shoe web and against shifting of the shoe axially with respect to the feed wheel discs.

2. In a machine for grinding off the lining of an arcuate brake shoe, a base, a carriage mounted on said base for endwise movement relative to said base, a grinding wheel mounted

stationarily at one end of the base and the carriage, a transverse shaft journaled on said carriage, means operatively connected to said shaft for rotating said shaft, a feed wheel fixed on one end of said shaft in the plane of said grinding wheel, said feed wheel comprising a pair of axially spaced discs having peripheral edges on which a brake shoe is adapted to be circumferentially engaged with the web of the shoe extending radially inwardly from the shoe into the space between the discs, first securing means on said discs for removably securing the brake shoe on the peripheral edges of the discs, and second securing means on said discs engageable with opposite sides of the shoe web, adjusting means connected between said base and said carriage for adjusting said carriage endwise on the base for engaging the lining of the brake shoe with the grinding wheel, said first securing means comprising magnets circumferentially spaced around the peripheral edges of said discs, said second securing means comprising radial pivot pins on the peripheral edges of the discs, locking discs mounted on said pivot pins to swing toward and away from adjacent sides of the shoe web, and locking members on said carriage extending along opposite sides of said feed wheel and engageable with the locking discs to hold the locking discs in engagement with the shoe web and against shifting of the shoe axially with respect to the feed wheel discs.

3. In a machine for grinding off the lining of an arcuate brake shoe, a base, a carriage mounted on said base for endwise movement relative to said base, a grinding wheel mounted stationarily at one end of the base and the carriage, a transverse shaft journaled on said carriage, means operatively connected to said shaft for rotating said shaft, a feed wheel fixed on one end of said shaft in the plane of said grinding wheel, said feed wheel comprising a pair of axially spaced discs having peripheral edges on which a brake shoe is adapted to be circumferentially engaged with the web of the shoe extending radially inwardly from the shoe into the space between the discs, first securing means on said discs for removably securing the brake shoe on the peripheral edges of the discs, and second securing means on said discs engageable with opposite sides of the shoe web, adjusting means connected between said base and said carriage for adjusting said carriage endwise on the base for engaging the lining of the brake shoe with the grinding wheel, said carriage having an ejecting lever pivoted thereon having a free end portion positioned between the feed wheel discs, said free end portion being arranged to be engaged by the brake shoe web as the feed wheel is rotated so as to disengage said first and second securing means and free the brake shoe from the peripheral edges of the feed wheel discs.
